[57] CLAIM

The ornamental design for a combined card and pocket electronic accessory case, as shown.

DESCRIPTION

FIG. 1 is a top plan view of a combined card and pocket electronic accessory case in a closed state, showing my new design;

FIG. 2 is a bottom plan view;

FIG. 3 is a left end elevational view;

FIG. 4 is a front elevational view;

FIG. 5 is a right end elevational view;

FIG. 6 is a rear elevational view;

FIG. 7 is a top plan view showing the claimed case in an open state; and

FIG. 8 is a perspective view showing the claimed case in an opened state.
